US00D627616S

(12) **United States Design Patent**
Whitehead et al.

(10) **Patent No.:** US D627,616 S
(45) **Date of Patent:** ** Nov. 23, 2010

(54) **POWER TOOL**

(75) Inventors: **John Francis Whitehead**, Jerilderie (AU); **Jon Seddon**, Surrey Hills (AU)

AU 199051441 10/1990

(73) Assignee: **Whitehot Solutions Pty. Ltd.**, Jerilderie (AU)

(Continued)

(**) Term: **14 Years**

(21) Appl. No.: **29/338,904**

(22) Filed: **Jun. 19, 2009**

(30) **Foreign Application Priority Data**

Apr. 7, 2009 (AU) 11195/2009

(51) **LOC (9) Cl.** **08-05**

(52) **U.S. Cl.** **D8/69**

(58) **Field of Classification Search** ..... D8/61-70; 81/57.11, 429, 454-456, 469, 489; 173/13, 173/46, 104, 114, 167-173, 178, 201, 211, 173/213, 214, 217, 198; 227/8, 113, 114, 227/120, 130, 136, 142; 310/50; 408/20, 408/35, 117, 124, 125, 234, 241 R, 58, 67; 451/358; 7/158, 165

(57) **CLAIM**

The ornamental design for a power tool, as shown and described.

DESCRIPTION

FIG. 1 is a front perspective view of a power tool.

FIG. 2 is a rear perspective view of the design of FIG. 1.

FIG. 3 is a left side view of the design of FIG. 1.

FIG. 4 is a right side view of the design of FIG. 1.

FIG. 5 is a front view of the design of FIG. 1.

FIG. 6 is a rear view of the design of FIG. 1.

FIG. 7 is a top view of the design of FIG. 1; and,

FIG. 8 is a bottom view of the design of FIG. 1.

The features shown in broken lines are for illustrative purposes only and do not form part of the claimed design.

1 Claim, 8 Drawing Sheets
